J. HELSTROM.

SOAP BEATER.

APPLICATION FILED MAY 4, 1915.

Patented Mar. 14, 1916.

UNITED STATES PATENT OFFICE.

JOHN HELSTROM, OF NEW YORK, N. Y.

SOAP-BEATER.

1,175,446.

Specification of Letters Patent.

Patented Mar. 14, 1916.

Application filed May 4, 1915. Serial No. 25,775.

To all whom it may concern:

Be it known that I, JOHN HELSTROM, a citizen of the United States, residing at New York, in the county of New York and State 5 of New York, have invented certain new and useful Improvements in Soap-Beaters, of which the following is a specification.

This invention relates to improvements in device for rapidly agitating an article, such 10 as a cake of soap in the water in which dishes or like articles are to be washed, and for like purposes, and has for one of its objects to simplify and improve the construction and increase the efficiency and utility of a device 15 of this character.

Another object of the invention is to provide a simply constructed device in which the pieces of soap or other article may be disposed and rapidly agitated and the receptacle recharged with the soap.

With these and other objects in view, the invention consists in certain novel features of construction as hereafter shown and described and then specifically pointed out in 25 the claims; and in the drawings illustrative of the preferred embodiment of the invention Figure 1 is a front elevation of the improved device; Fig. 2 is a side view partly in section; Fig. 3 is a perspective view of the 30 upper combined frame and shaft holding member. Fig. 4 is a perspective view of the lower combined frame and shaft holding member.

The improved device comprises a supporting frame, preferably formed from a single 35 piece of a rod or heavy wire and bent into a handle 10 at one end and into hoop-like form 11 at the opposite end. Adjacent to the handle portion 10, the rod members are disposed in parallel relation and in close 40 proximity for a distance as represented at 12 and thence distended and directed for a distance in parallel relation but spaced apart as shown at 13 and merging into the hoop-like 45 portion 11. The frame is thus constructed from a single rod with the terminals united preferably at the lower end of the hook-like portion 11, as indicated at 14, the joint being made by soldering, brazing, electric 50 welding or the like.

At the upper ends of the distended portions 13 of the frame a coupling member 15 is disposed, and a similar coupling member 16 is disposed intermediate the portions 13. The coupling member 15 is first construct-

ed as shown in Fig. 3 with bearings near the ends for the members 13, and secured in place by bending the portions of the member 15 externally of the bearings around the members 13. The bearing member 15 is 60 provided with a transverse aperture to receive a stud represented at 17 which carries a relatively large gear wheel 18, the gear wheel having an operating handle 19. The bearing member 16 is substantially the 65 same in form as the bearing member 15 as illustrated in Fig. 4, except that it has a vertical aperture to receive a vertical shaft 20. The member 15 is likewise provided with a step in its lower side to receive the 70 upper end of the shaft 20. The inner walls of the bearings of the members 15—16 extend at right angles to the transverse plane of the member, so that the solid intermediate portions of the members 15—16 are presented to the portions 13 of the frame, to effectually prevent inward movement, while the bent terminals prevent outward movement. Mounted upon the shaft 20 is a pinion 21 to engage the teeth of the gear 18, 80 the pinion being rigidly connected to the shaft and serving likewise as a stop collar to prevent downward movement of the shaft. At its lower end, the shaft 20 is provided with a hoop-like portion 22 somewhat 85 smaller than the hoop-like portion 11 of the frame and rotative therethrough when the shaft is rotated by motion imparted to the gear 18 and its pinion 21.

The members 15 and 16 are immovably 90 connected to the portions 13 of the frame so that the pinion 21 coacting with the members 15—16 will retain the shaft 20 from vertical movement relative to the frame 95 while at the same time leaving the shaft free to rotate in the frame members. At one side, the member 22 of the shaft is provided with a semi-globular net work of relatively small wires 23 which are rigidly coupled thereto and rotate with the shaft. The shaft 100 20 and the hoop-like portion 22 of the shaft are preferably bent from a single rod with the terminal of the hoop-like portion soldered or otherwise secured to the body of the shaft, as represented at 24. Mounted to 105 swing upon the hoop-like portion 22 of the shaft is a cage corresponding to the semi-globular portion 23 and constructed of a supporting frame indicated conventionally at 25 and conforming in outline substan- 110

tially to the portion 22 of the shaft. The frame 25 is formed from a single section of wire bent into substantially hoop-like shape with eyes 26 at the terminals which engage 5 around the lower part of the frame portion 11 and are thus arranged to swing thereon. At the side opposite to the eyes 26 the member 25 is bent into an upwardly directed loop 27 with the sides of the loop again bent 10 into smaller and spaced loops 28-29 which engage the sides of the shaft 20 at its juncture with the hoop-like portion 22. The handle member 27 and the loops 28-29 engage the shaft 20 with sufficient force to 15 hold the cage-like member in position. The portion 25 of the cage is provided with semi-globular wire portions 30 corresponding to and opposing the semi-globular wire portions 23 of the shaft. The two semi-globular wire portions 23-30 thus form a 20 complete cage in which the soap is disposed.

By this simple construction, it will be obvious that an effectual device is produced 25 whereby one or more pieces of soap deposited in the cage member may be rapidly rotated in the water and the dissolving of the soap completed in a much less time and more thoroughly and completely commingled with the water, as the rapid rotation of the cage not only expedites the dissolving of the soap but likewise mixes the dissolved soap thoroughly with the water. 30

The improved device is simple in construction, can be inexpensively manufactured of any suitable material and of any 35

suitable size, and provides an effectual device for the purposes specified.

Having thus described the invention, what is claimed as new is:-

1. In a device of the class described, a frame formed of sides spaced apart, supports spaced apart and each provided with laterally opening bearings to engage said frame sides, the inner walls of said bearings extending at right angles to the longitudinal plane of said supports and secured to the frame sides by bending the outer portions of the bearings over the same, said supports having bearings adapted to receive driving members.
2. In a device of the class described, a supporting frame, a driving member mounted for rotation relative to said frame and having a hoop-shaped terminal, a half cage carried by said hoop-shaped terminal, a half cage frame formed of a single length of wire bent intermediate its ends into a loop with the sides reversely curved and having terminal eyes engaging around the hoop-shaped terminal, and a plurality of outwardly curving bars spaced apart and connected at their ends to the sides of the half cage frame, said loop being adapted to frictionally engage the driving member.

In testimony whereof I affix my signature in presence of two witnesses.

JOHN HELSTROM. [L.S.]

Witnesses:

CLARENCE E. BAKER,
GUSTAV SANDUES.
